LINE FEED ALARM FOR FRICTION FEED
TELEGRAPH PAGE PRINTERS
Robert J. Dunlavy, Palatine, and Theodore I. Przysiecki,
Mount Prospect, Ill., assignors to Teletype Corporation,
Skokie, Ill., a corporation of Delaware
Filed Apr. 13, 1962, Ser. No. 187,289
9 Claims. (Cl. 178—42)

This invention relates to alarm devices for printing 10 telegraph page printers and more particularly to a line feed alarm device for friction feed telegraph page printers.

In printing telegraph page printers wherein the web of paper is fed by friction rather than by sprockets entering preformed holes in the web there is a possibility that the web will not be fed when a line feed signal is received in the apparatus due to slippage between the platen and web of paper. This could result from maladjustment of the friction feed device, the absence of paper in the apparatus or other causes and would result in superposing one line of printing, or more, on top of the preceding line of printing or printing on the platen. This would cause the obliteration or loss of the printed message and consequently, there is a need for some means for periodically checking the effective operability of the friction feed mechanism.

Accordingly, the principal object of the present invention is the detection of the failure of a line feed mechanism of the friction feed type in printing telegraph apparatus to function.

Another object of the invention is to provide, in a telegraph page printer, a device responsive to a given signal to check the effectiveness of the web feeding mechanism of the printer.

Still another object of the invention is to provide a line feed alarm device for friction feed telegraph printers which will call attention to the fact that, although the platen is rotated the web of recording medium is not fed by it.

In accordance with the preferred embodiment of the invention a piercing member is provided which, upon receipt of a predetermined signal in the apparatus, will be moved to pierce the paper so that when the paper is moved by the platen the piercing member will be rocked about its support to remove one end of the piercing member from the path of an oscillatable contact actuating lever which normally tends to follow the movement of the support for the piercing member whereby if the piercing member is not rocked by the paper as a consequence of the movement of the paper by the platen, the contact actuating lever will not be permitted to follow the movement of the racks and will not operate a switch thereby causing an alarm to be actuated.

A complete understanding of the invention may be had by reference to the following description when considered in conjunction with the accompanying drawing wherein:

FIG. 1 is a partial vertical sectional view showing the line feed mechanism of a friction feed type of page printer equipped with the device of the present invention;

FIG. 2 is a fragmentary view taken substantially along the line 2—2 of FIG. 1 in the direction of the arrows showing the mechanism for actuating the piercing member;

FIG. 3 is a fragmentary view taken substantially along the line 3—3 of FIG. 1 in the direction of the arrows showing the line feed failure detecting mechanism in plan, and

FIGS. 4 and 5 are fragmentary views similar to FIG. 1 showing the various positions assumed by the component parts of the device during their operation.

2

The line feed mechanism according to the present invention is designed to be embodied in a telegraph page printer of the type disclosed in United States Patent No. 2,505,729, granted April 25, 1950, to W. J. Zenner, as modified by the platen driving mechanism for effecting line feeding operations disclosed in United States Patent No. 2,667,256, granted January 26, 1954, to B. F. Madsen. The disclosure of these two patents is incorporated herein by reference and made a part hereof for the disclosure of the line feeding mechanism per se.

Referring now to the drawings wherein like reference characters designate the same parts throughout the several views and having reference to the patent to B. F. Madsen mentioned hereinbefore, it will be seen that the line feed mechanism comprises a gear 11 fixed to the platen 12 of the printer and a pair of rack members 13 and 14. The gear 11 rotates with the platen 12 and the rack members 13 and 14 will alternately engage with the teeth of the gear 11 with a slight overlap of engageability being provided to impart substantially uniform motion to the gear 11 and platen 12. These rack members 13 and 14 are connected to eccentrics 16 and 17, respectively, and power for operating the racks is derived from a main shaft 18. These rack members 13 and 14 control the driving of the platen 12 by sliding and oscillating on a pivot 19 as described in the above-mentioned patent to B. F. Madsen.

The mechanism for detecting the failure of the line feed mechanism to feed a web of paper 21 is mounted on the main framework of the printer, being supported from a side plate 20. A main support bracket 25 is suitably fixed to the side plate 20 and supports the components which comprise the line feed alarm device of the present invention. A magnet supporting member 26 is fixed to the bracket 25 and supports the actuating coil 27 of an electromagnet 28 and also pivotally supports an armature 29 of the electromagnet 28. The armature 29 is normally biased to the position shown in FIG. 2 by a contractile spring 30 which is attached to a stud 31 mounted on the magnet supporting member 26 and to the left end of the armature 29. The right end (FIG. 2) of the armature 29 extends into a slot 32 in a pivoted lever 33. The pivoted lever 33 is oscillatable about a pivot stud 34 that projects from the main support bracket 25 and supports a piercing member 40 at its upper end.

The pivoted lever 33 has a platform 41 formed on its upper end from which two guide fingers 42 and 43 extend upwardly through apertures 44 and 45 in the piercing member 40 to guide the piercing member 40. The piercing member 40 is held on the platform 41 by a light compression spring 46 which bears against the upper surface of the piercing member 40 and the lower surface of the head of a screw 47 which is attached to the platform 41 and has its shank extending through an aperture 38 in the piercing member 40. The aperture 38 in the piercing member 40 is slightly larger in diameter than the shank of the screw 47 whereby, while the spring 46 urges the piercing member 40 to lie flat on the platform 41, the piercing member 40 may be rocked with respect to the platform 41, being guided by the shank of the screw 47 and guide fingers 42 and 43.

A guide bracket 48 is mounted on the main support bracket 25 and is provided with a pair of guide members 49 which are disposed upon opposite sides of the pointed left end (FIG. 3) of the piercing member 40 to guide the piercing member in its movement toward the web of paper 21. The web of paper 21 is held against the platen 12 by a shoe 50 (FIGS. 1 and 4) which extends across the platen 12 and is suitably supported on the framework of the apparatus by a shoe support 51 to hold the paper 19 in engagement with the platen 12 across the entire length of the platen.

When the electromagnet 28 is de-energized as shown in FIGS. 1 and 2 of the drawings, the piercing member 40 will be maintained in the position shown in FIG. 1 where its right end is aligned with a laterally extending arm 52 of a contact actuating lever 53. The contact actuating lever 53 which is pivotally mounted on a pivot stud 54, is biased to rock counterclockwise about stud 54 by a spring 39 and has a transversely extending arm 55 lying in the path of a lateral extension 56 of the pivoted lever 33. The contact actuating lever 53 is also provided with two other laterally extending arms 57 and 58. The arm 57 extends into cooperative relationship with an insulator 59 mounted at the free end of a contact spring 60 as seen most clearly in FIG. 4. The contact spring 60 is biased to hold its contact 61 out of engagement with a contact 62 on a contact spring 63. Both the contact spring 60 and the contact spring 63 are mounted in a suitable insulating support 65.

The laterally extending arm 58 extends into the path of the upper ends of the two rack members 13 and 14 whereby in each feeding cycle of the line feed mechanism the blocking lever 53 will be engaged by one or the other of the racks 13 and 14 and will be blocked from rocking counterclockwise about its pivot stud 54 by the racks at that time in the line feeding operation of the apparatus but will be permitted to rock counterclockwise when the racks are both rocked about the pivot 19 in a counterclockwise direction. It should be noted that the laterally extending arm 57 extends through an aperture 66 in the main support bracket to position to engage the insulator 59.

Operation

In the normal operation of a page printer apparatus such as that described in the aforementioned patents to W. J. Zenner and B. F. Madsen, the receipt of a line feed signal in the printing telegraph apparatus will initiate a cycle of rotation of the eccentrics 16 and 17 and a combination rocking motion and vertical reciprocation will be imparted to the rack members 13 and 14, the reciprocation and rocking motion being controlled by the pivot 19 which serves to guide the racks 13 and 14. The platen, being driven by the gear 11, will have step-by-step rotation imparted to it each time the rack members 13 and 14 are operated and normally will feed the web of paper 21 to present a blank line of it to the printing mechanisms. When it is desired to check the line feed mechanism to determine whether or not it is operating properly, the electromagnet 28 may be energized in any suitable manner, for example, by the transmission over a telegraph line (not shown) of a series of code combinations calling for the operation of this electromagnet in the manner well known in the art. Then, while the electromagnet 28 is held energized, line feed signals may be fed to the apparatus to cause the rack members 13 and 14 to be operated for driving the platen 12. When the electromagnet 28 is energized the pivoted lever 33 will be rocked counterclockwise about the pivot stud 34 to move the lateral extension 56 of it out of engagement with the transversely extending arm 55 of the contact actuating lever 53 thereby to release the lever 53. When this occurs the pivoted lever 33 will assume the position shown in FIG. 4 wherein the extension 56 is disengaged from the transversely extending arm 55 and the contact actuating lever 53 under the influence of its spring 39 will tend to follow pivoted lever 33. The pivoted lever 33 in being rocked counterclockwise will carry the piercing member 40 with it to cause the pointed left end of the piercing member 40 to pierce the paper. When the first line feed signal is received in the apparatus with the piercing member 40 entered into the web of paper 21, the piercing member 40 will be rocked in a clockwise direction with respect to the platform 41 and will assume the position shown in dotted lines at 67 in FIG. 4.

In printers of the type disclosed in the aforementioned

patents to W. J. Zenner and B. F. Madsen both racks 13 and 14 return to full engagement with the gear 11 after each feeding operation. During the feeding operation, one or the other of the racks 13 and 14 will move to the position shown in FIG. 5 preparatory to re-engagement with and operation of the gear 11. Thus, before the piercing member 40 is rocked with respect to the platform 41, the contact actuating lever 53 will be disengaged from the right end of the piercing member 40 by one or the other of the racks engaging its laterally extending arm 58 as shown in FIG. 5 so that there will be a minimum of resistance of the rocking movement of the piercing member 40. At the end of the line feed operation the piercing member 40 will be in the position shown in dotted lines in FIG. 4 and solid lines in FIG. 5 provided a proper line feed of the web of paper 21 has taken place. If the piercing member 40 has pierced the paper and the piercing member 40 has not been rocked with respect to the platform 41, its right end will be in blocking engagement with the laterally extending arm 52 of the contact actuating lever 53 and will prevent the lever 53 from rocking counterclockwise about its pivot stud 54. This will result in the pair of contacts 61 and 62 being held out of engagement one with the other and an alarm will be actuated. It will be understood that after a line feed signal has been received in the apparatus an alarm condition will prevail unless the contact spring 60 is moved to make contact between the contacts 61 and 62. When the contacts 61 and 62 are permitted to close, indicating that there has been a proper feeding of the web of paper 21, no alarm will be given and the apparatus will be in condition to receive line signals. Release of the electromagnet 28 will cause the pivoted lever 33 to be rocked back to the position shown in FIG. 1 to withdraw the piercing member 40 from the paper and to block counterclockwise movement of the contact actuating member 53 by moving its lateral extension 56 to the position shown in FIG. 1.

Although only one embodiment of the invention is shown in the drawings and described in the foregoing specification it will be understood that invention is not limited to the specific embodiment described but is capable of modification and rearrangement and substitution of parts and elements without departing from the spirit of the invention.

What is claimed is:

1. A line feed alarm device for use with a telegraph page printer having a line feed mechanism for feeding a web of record material step-by-step to bring succeeding areas of the web into a printing position comprising
  - (a) a control magnet operated by receipt in the printer of a predetermined code combination of signals,
  - (b) a pivoted lever held in one position by said magnet when said magnet is de-energized and moved to a second position upon energization of said magnet,
  - (c) a web engaging member carried by said pivoted lever and moved to position to be driven by the web by said pivoted lever when said pivoted lever is moved to said second position,
  - (d) contact operating means urged to move with said pivoted lever, said web engaging member and the line feed mechanism having portions which block such movement in certain of the operative positions of said member and of said mechanism, and
  - (e) alarm means including a pair of contacts operated by said contact operating means when the contact operating means is unblocked by the web engaging means having been driven by the web and the line feeding mechanism is operated and the pivoted lever is in said second position.
2. A line feed alarm device for use with a telegraph page printer having a line feed mechanism for feeding a web of record material step-by-step to bring succeeding areas of the web into a printing position comprising

- (a) a control magnet operated by receipt in the printer of a predetermined code combination of signals,
- (b) a pivoted lever held in one position by said magnet when said magnet is de-energized and moved to a second position upon energization of said magnet,
- (c) a web engaging member oscillatably mounted on said pivoted lever and moved into engagement with the web by said pivoted lever when said pivoted lever is moved to said second position whereby movement of the web will oscillate the web engaging member from a blocking to an unblocking position,
- (d) contact operating means normally blocked from operating by said web engaging member in the blocking position and by said pivoted lever in said first position, and
- (e) alarm means including a pair of contacts operated by said contact operating means when the pivoted lever is in said second position and the web piercing member is oscillated to the unblocking position.

3. Apparatus according to claim 2 wherein said contact operating means is provided with an arm disposed in the path of said line feed mechanism for movement by said line feed mechanism whereby said line feed mechanism momentarily moves said contact operating means away from said web engaging member to permit the web engaging member to be readily moved by the web.

4. A line feed alarm device for use with a telegraph page printer having a line feed mechanism for feeding a web of record material step-by-step to bring succeeding areas of the web into a printing position comprising

- (a) a control magnet operated by receipt in the printer of a predetermined code combination of signals,
- (b) a pivoted lever held in one position by said magnet when said magnet is de-energized and moved to a second position upon energization of said magnet,
- (c) a web piercing member carried by said pivoted lever and oscillatable with respect thereto and moved to pierce the web by said pivoted lever in moving to said second position whereby movement of the web will oscillate the web piercing member to an unblocking position,
- (d) a contact actuating lever blocked from operating by said web piercing member when said web piercing member is not oscillated by the web, and
- (e) alarm means including a pair of contacts operated by said contact actuating lever to indicate that the web piercing means has not been driven by the web when the line feeding mechanism was operated.

5. In a telegraph page printer having line feed mechanism for imparting a step of rotation to a platen to feed a record web one step in response to each line feed signal received in the printer; an alarm device for detecting the failure of the feed mechanism to impart movement to the web comprising

- (a) a pair of alarm contacts,
- (b) an actuating lever spring biased to operate said contacts,
- (c) a pivoted lever for normally holding said contact actuating lever in unactuated position,
- (d) a pivot for supporting said pivoted lever,
- (e) means engageable with the web and pivotally mounted on the pivot lever for movement by the web when the pivoted lever is moved about its pivot,
- (f) a selectively actuated member for rocking said pivoted lever about its pivot to engage said means with the web,
- (g) a blocking arm on the contact actuating lever for engagement with one end of said means to block

movement of the contact actuating lever when a line feed signal is received and the web does not move to move said means about its pivot on the pivoted lever.

6. In a telegraph page printer having line feed mechanism for imparting a step of rotation to a platen to feed a record web one step in response to each line feed signal received in the printer; an alarm device for detecting the failure of the feed mechanism to impart movement to the web comprising

- (a) a pair of alarm contacts,
- (b) a main lever,
- (c) a pivot pin for supporting said main lever for oscillation,
- (d) means for moving said main lever from one position to a second position,
- (e) a contact actuating lever spring biased to follow the movement of said main lever to its second position to operate said contacts,
- (f) a web engaging member pivotally mounted on said main lever for engagement with and pivotal movement by the web when the main lever is moved to the second position,
- (g) an arm extending from said contact actuating lever for engagement with an end of the paper engaging member to prevent operation of the alarm contacts when the main lever engages the web engaging member with the web and the web is not fed in response to a received line signal, and
- (h) means for actuating the main lever moving means.

7. Apparatus according to claim 5 wherein the web engaging means has a knife edge for penetrating the paper and its end opposite the knife edge blocks movement of the contact actuating lever when the web fails to move upon receipt of a line signal in the apparatus.

8. Apparatus according to claim 6 wherein the web engaging member is a piercing member which is spring urged to maintain a fixed relation with respect to the main lever but may be rocked with respect to the main lever by movement of the web after the web engaging member has pierced the web to move the end of the web engaging member opposite to its web engaging end out of the path of movement of the blocking arm on the contact actuating lever.

9. Apparatus according to claim 6 wherein the web engaging member is a piercing member which is spring urged to maintain a fixed relation with respect to the main lever but may be rocked with respect to the main lever by movement of the web after the web engaging member has pierced the web to move the end of the piercing member opposite to its web engaging end out of the path of movement of the blocking arm on the contact actuating lever, and the actuating means for the main lever is the armature of an electromagnet operated by receipt in the printer of a predetermined code combination of signals and serves to rock the main lever to a position to carry the piercing member into the web so that the piercing member will be rocked about the main lever when the web

is moved one step by the line feed mechanism to unblock the contact actuating lever and permit it to operate the alarm contacts.
